PULVERIZER

Martin Frisch, New York, N. Y., assignor to
 Foster Wheeler Corporation, New York, N. Y.,
 a corporation of New York

Application May 4, 1932, Serial No. 609,167

27 Claims. (Cl. 83—11)

My invention relates to the art of pulverizing and particularly to the art of pulverizing coal or similar material by subjecting it to the action of rapidly rotating members.

5 One of the objects of my invention is to provide a pulverizing apparatus or mill wherein the material to be pulverized is subjected a plurality of times to the action of the same rotating members, whereby extremely fine pulverizing is effected by an apparatus of minimum size.

Another object of my invention is to eliminate foreign materials, thereby minimizing the danger of breakage of pulverizing members.

A further object of my invention is to increase 15 the air flow through a pulverizing mill so that the mill may be operated with a smaller exhauster, or the same exhauster may deliver more air therethrough than was formerly the case.

Other objects and advantages of my invention 20 will be apparent from the following description considered in connection with the accompanying drawings, which form a part of this specification, and on which:

Fig. 1 is a central vertical longitudinal section, partly in elevation, through the main portion of a mill embodying the invention;

Fig. 2 is a transverse sectional view, taken on line 2—2 of Fig. 1;

Fig. 3 is a transverse sectional view taken on line 3—3 of Fig. 1;

Fig. 4 is a fragmentary view of certain parts shown in Fig. 1;

Fig. 5 is a view similar to Fig. 4 but showing a modified arrangement of certain parts;

Fig. 6 is a view taken on line 6—6 of Fig. 5;

Fig. 7 is a cross-sectional view taken on line 7—7 of Fig. 6;

Fig. 8 is a view taken on line 8—8 of Fig. 5; and

Fig. 9 is a view taken on line 9—9 of Fig. 5.

In the embodiment of the invention illustrated by Figs. 1—4, reference character 10 designates a bed-plate upon which members 11 and 12 are mounted. A pair of supports 13 and 14 are also mounted on the bed-plate. A casing 15 made in two parts 15' and 15'' is supported by the members 11 and 12. The casing is provided with end walls 17 and 63, each being formed with a central opening therethrough. An exhauster casing 16 is supported by end wall 17 and the bed-plate.

Extending through the casings 15 and 16 is a shaft 18 mounted in suitable bearings 20 and 21 carried by supports 13 and 14, respectively.

Mounted on shaft 18 within casing 15 is a hub 32. In the embodiment shown, two annular

discs or wheels 30 and 31 are rigidly secured to hub 32 by means of bolts 33 and 34, respectively, and by means of rings 35 and 36 secured to hub 32 by bolts 37 and 38, respectively. Wheel 31 has a larger diameter than wheel 30. A plurality of hammers 40 and 42 are pivotally secured to wheels 30 and 31 by pins 41 and 43, respectively, so as to have limited swinging movement about the pins.

Arranged around wheel 31 and hammers 40 is 10 a scroll-shaped member 62 made up of two parts 62' and 62'' supported on end wall 63 by bolts 64. A pocket 82 for tramp metal or other foreign material such as stone is formed in the scroll-shaped member 62 between parts 62' and 62''. A 15 series of louver grids or targets 83 are provided in the side of the pocket. These grids permit the passage of air and partially pulverized coal but stop larger particles of foreign material, which thus are trapped. A drop gate 84 is fixed 20 to a shaft 85. Shaft 85 extends through the end wall 63 and a boss 86. A lever 81 held in place by a stop 88 is fixed to shaft 85. The rotation of shaft 85 causes any material trapped in the pocket to be discharged through an opening 90 25 in the casing 15. Communicating with opening 90 is a conduit 91. The opening of the conduit is closed by a slide 92, which may be raised to remove tramp metal.

Wheel 30 and its associated parts constitute 30 a first stage, and wheel 31 and its associated parts constitute a second stage. The first and second stages constitute what may be termed a crushing zone.

Fine grinding elements constitute a third stage, 35 conveniently termed a fine grinding zone, which is arranged adjacent to the crushing zone. These elements comprise essentially a set of stationary radial bars 44 and a set of rotating radial bars 45. Between the stationary bars 44 are spacing 40 means or webs 50, 51 and 52. A plate 53 is made integral with, or secured to, webs 50 and 51. There is thus formed by the plate 53 and webs 50 and 51 a series of pockets which provide means for redirecting air and pulverized material. The 45 stationary bars 44, webs 50, 51 and 52 and plate 53 are conveniently made in four sections, two of which, designated by reference characters 46 and 47, are shown bolted together at 48. Each section may be cast in one piece and is bolted to 50 the pulverizer casing 15' by bolts 54 and 55. The four sections taken together constitute the set of stationary bars.

The rotating bars 45 are mounted on a disc 56 and are held rigidly in place by bolts 57. The 55

disc is secured to hub 32 by bolts 58. An additional fastening ring 60 prevents disc 56 from moving axially. Disc 60 is fastened to the hub by screws 61.

5 The bars have been shown as round but it will be understood that they may be given any desired cross-section, such as square or triangular. As shown, there are twenty-four stationary bars and twenty-three rotating bars. This prevents 10 the bars from ever matching each other. A greater or smaller number of bars may be used, and instead of having more stationary bars than rotating bars, the number of rotating bars may be greater. In other words, it is preferable that 15 the number of stationary bars should differ from the number of rotating bars in order that there can be no position in which all the bars of one group are axially in line with bars of the other group.

20 A horizontally split liner 65 surrounds the pulverizing elements in the crushing zone. A horizontally split end wall liner 66 is secured adjacent to end wall 63 outside of the scroll-shaped liner 62 and is held in place by the liner 65 together with a flange 67 on liner 62. To the left of web 52, as viewed in Fig. 4, is the liner 68. A partition 70 formed with a central opening is secured to the pulverizer casing 15. The liners and partition 70 may be made of steel or other 30 suitable wear resisting material.

A classifier cone 71 and an annular member 72 are bolted to partition 70 adjacent to the central opening therethrough by bolts 73. Between the annular member 72 and the partition 70 is a plurality of shims 74 for spacing the annular member 72 away from the rotating bars 45. Associated with the classifier cone 71 is a set of radially extending vanes 80. The vanes are mounted on a hub 81 which is keyed to the shaft 18.

40 All parts fastened to the upper half of the pulverizer casing are split horizontally so that by unfastening bolts 75 and 76 the entire upper half of the pulverizer with the exception of parts keyed to shaft 18 may be swung upwardly on the pivot 45 of the hinge 78. This allows inspection of the interior of the pulverizer and permits replacement of certain parts which may be worn out.

A conduit 94 communicates through an opening 93 with the space between partition 70 and the end wall 17. The end of the conduit 94 may be closed by an adjustable slide 95. Opening 93 will hereinafter be referred to as an air inlet and admits air between the fine grinding zone and the exhauster. By adjusting slide 95 the size of 55 the opening of the air inlet may be changed to vary the amount of air admitted at this point. Where the pulverizing mill is used to supply pulverized coal directly to a burner it is desirable to supply additional air through this inlet. It will 60 be understood that the conduit 94 may be connected with any suitable source of heated air.

Mounted on shaft 18 within exhauster casing 16 is a hub 24 having arms 25 to which are secured fan blades 26. Casing 16 is formed with a centrally located inlet opening 22 and a tangentially located discharge conduit 23. A liner 28 is provided within casing 16.

A feed inlet chute 96 is fastened to end wall 63 by bolts 97 and communicates with the central 70 opening in the end wall. A conduit 100 from chute 96 to a table feeder 98 is fastened to the feeder. Table feeder 98 comprises a flat circular table 101 fitting closely in a circular feeding chamber 102. The table is rotated by a shaft 103 which is slidably mounted in a worm gear 104. A

bevel gear 105 is mounted on the shaft 18. A transverse shaft 106 carries a worm 107 meshing with worm gear 104 and a bevel gear 108 meshing with bevel gear 105. The arrangement of the bevel and worm gearing is such as to materially 5 reduce the speed between shafts 18 and 103. A bracket 110 rotatably supports worm gear 104 and shaft 106. A deflecting cone 111, located above the table, is keyed to the shaft 103. Rotatably carried upon this deflecting cone is a scraper 112 10 which is held from rotating by a stationary abutment 113. A lever 114 pivotally mounted on bracket 110 engages a collar on shaft 103 for raising and lowering the table 101 to vary the amount of material entering the feeding chamber 102 15 from hopper 117. The lever 114 is held in any desired position by engaging a latch 115 with rack 116. A slide 118 held in adjustment by wing nut 120 varies the quantity of air fed to the pulverizer with the material to be pulverized. 20

Fig. 5 shows a modification of certain parts in the fine grinding zone. Like reference characters in Figs. 1 and 5 indicate similar elements.

The stationary bars 121 may be cast in four sections with webs 122, 123 and 124 therebetween. 25 Upper and lower pairs of sections are bolted together at 125. Between webs 123 and 124 there are more bars than between webs 122 and 123. As shown, there are twice as many bars between webs 123 and 124 as there are between webs 122 30 and 123, but this proportion may be varied. This allows a wide clearance 126 for air and pulverized material between webs 122 and 123. Each section is bolted to the pulverizer casing 15 between liners 65 and 68 by bolts 127 and 128. 35

The rotating radial bars 130 are made separate and interchangeable. These bars are provided with a neck portion 131 around which a pair of clamps 132 fit. As there are, in the device shown, twenty-three rotating bars, eleven pairs of clamps 40 are constructed to hold a pair of bars each, while one pair of clamps 133 holds only a single bar. The clamps are fastened rigidly to the disc 56 by bolts 134.

A flat annular disc 135 and a ribbed annular 45 disc 136 are fastened to the wheel 34 by bolts 137. The shape of ribs or vanes 138 may be seen in Fig. 7. An annular boss 140 serves to space the ribbed disc 136 from the flat disc 135. A plurality of hammers 141 are pivoted on bolts 142 50 to swing between the discs 135 and 136. The hammers are equally spaced around the periphery of the impact wheel as in the embodiment shown in Figs 1 and 2.

The ribs or vanes on disc 136, besides causing 55 a portion of the air and pulverized material to be thrown outwardly toward the pulverizer casing, also cause flow to be again redirected into stationary and rotating bars.

The arrows in Figures 4 and 5 indicate in general the path of flow of air and pulverized material through the fine grinding zone. 60

The operation of the pulverizing mill is as follows:

For the purpose of illustration let it be assumed 65 that coal is the material to be pulverized. Relatively larger pieces of coal enter the feeder chamber 102 from the hopper 117. The coal falls on the rotating table 101 and is swept off into the chute 96 by the scraper 112. When lever 115 is in its lowermost position the capacity of the feeder is a maximum, since the position of the deflecting cone, which is varied by the lever, determines the quantity of coal falling through the hopper 70 discharge into the feeder chamber. 75

The coal leaves chute 96 and enters the first stage which is primarily designed to crush the coal as a result of impact between the hammers 40 and the pieces of coal. Any hard foreign matter, such as tramp metal, which is not broken up by impact with hammers 40 is thrown into the pocket 82 by the hammers or beaters 40. The air and coal is given a whirling motion by the rotation of wheel 30 and the hammers 40. This whirling motion is carried into the second stage through the discharge opening of the spiral chamber formed by the scroll-shaped member 62 surrounding the first stage wheel and hammers. Should any tramp metal or hard foreign body enter the second stage the hammers or beaters 42 strike it and cause it to be thrown through opening 90 into a collecting chamber provided by conduit 91. Any metal collected in pocket 82 may be emptied into opening 90 by rotating the drop gate 84 with lever 87. The metal is disposed of by raising slide 92 and removing it from the collecting chamber.

Hammers 42 in the second stage complete the crushing of the coal and accentuate the whirl of the mixture of coal and air, thus aiding the exhauster in drawing the mixture through the mill, while, at the same time brushing or distributing it through the stationary radial bars at the inlet to the third or fine grinding stage. These hammers also prevent accumulation or deposit of material in the bottom portion of the casing 15 to the right of the stationary radial bars, which would block or obstruct the entrance to the third stage.

The final pulverization of the coal occurs by the aid of grinding elements comprising the radial rotating bars 45 rotating closely to the set of stationary radial bars 44. The arrangement of the annular member 72 on end wall 70 and web or baffle 51 with plate 53 in the fine grinding zone is such that the air and coal leaving the second stage must pass three times across the stationary and rotating radial bars before entering the exhauster. The mixture leaving the second stage to enter the third stage must change from a radial direction to an axial direction in order to pass through the stationary radial bars 44. In this way the relative velocity between the coal to be pulverized and the rotating bars is kept at a maximum, which produces a maximum pulverizing effect. The path of the coal and air through the fine grinding zone is indicated by arrows. The main path takes the form of the letter S, the coal and air entering around the circumference between webs 51 and 52. They first pass across the radially outer portion of the stationary and rotating bars and the coal is thereby pulverized. They then are deflected by the partition 70 and annular member 72 and pass across the rotating and stationary bars again and into the pockets formed between adjacent stationary bars by webs 50 and 51 and plate 53. From these pockets the air and coal pass once again across the stationary and rotating bars to the central inlet 22 of the exhauster. It will be noted that this main path of travel is from the circumference toward the center and hence counter to the direction of centrifugal force which acts on the particles of coal due to the rotation in a radial plane imparted to them by the rotating bars. The result is that local eddies and whirls of particles caught between the flow of air tending to draw them to the center and centrifugal force tending to throw them to the circumference are set up. These eddies and whirls are represented by arrows 27 and 29 and

they result in the coal coming in contact with the rotating and stationary bars more often than would be the case if they were not present. Consequently, more grinding and pulverizing is accomplished. Furthermore, the centrifugal force 5 acting on the larger particles is greater than that acting on the smaller ones, and hence the larger particles are more apt to be caught in the eddies, whereby they are further pulverized. When the particles of coal are minute enough so that the 10 frictional drag of the air overcomes the centrifugal force, they will be withdrawn from the mill by the exhauster.

Between the mill and the exhauster is the classifier or rejector device comprising classifier cone 15 11 and radially extending blades 80 which prevents large particles from entering the exhauster. The blades 80 act more or less like the blades of a fan for continuing the rotary movement of the mixture of coal and air leaving the fine grinding 20 zone, and by centrifugal force throw the coarser material against the sides of the classifier cone which permits the return of the material to the fine grinding zone for further treatment.

The operation of the modification shown in 25 Fig. 5 is similar to the foregoing with respect to the first two stages, or crushing zone, but differs with respect to the third stage, or fine grinding zone. In this modification the mixture of coal and air discharged from the second stage enters 30 the first pass of the third stage between the outer group of stationary bars 121 and the rotating bars 130. After going through this first pass, the mixture is redirected by end partition 70 and annular member 72 and passes through the second 35 pass between rotating bars 130 and the inner group of stationary bars 121. The mixture at the end of this second pass is acted upon by the rotating ribs or vanes 138 mounted on the second 40 impact wheel 31. These rotating ribs cause a 45 portion of the mixture of air and coal to pass radially outwardly between the ribs and web 123, where this mixture joins the mixture coming from the second stage of the crushing zone and which is about to enter the first pass of the third stage. Hence, the portion of the mixture divided at the end of the second pass is recirculated through the first pass. The highest relative 50 velocity between the rotating and stationary bars is the section comprising the first pass, and hence 55 the maximum pulverizing effect is obtained by keeping material in this section until fine enough to be carried out of the fine grinding zone by the stream of air drawn therethrough by the exhauster.

The amount of additional air supplied through the damper controlled inlet 93 is determined by the degree of pulverization desired and the use to be made of the material pulverized. Inasmuch as the exhauster draws in a substantially constant 60 quantity of air, if more air is admitted through inlet 93, less air is drawn through the crushing and grinding zones of the mill and consequently what is drawn through has a lower velocity. This results in the coal being ground finer before 65 it is removed from the last stage, inasmuch as the low velocity air cannot remove larger particles against the action of centrifugal force. The additional air may be preheated if desired.

The pulverized coal discharged by the exhauster 70 may be collected and stored or it may be used directly by any suitable burner.

It will thus be seen that in both modifications the material to be pulverized is passed a plurality of times across the stationary and rotating bars. 75

It will be understood that the members constituting the fine grinding stage may be employed independently of the specific means shown for performing the preliminary crushing. The nature 5 of the material may be such that it may be fed directly to the apparatus constituting the third stage of the mill above described.

It will, of course, be understood that various 10 changes may be made in the form, details, arrangement and proportions of the parts without departing from the scope of my invention, which, generally stated, consists in a device capable of carrying out the objects above set forth, and in the novel parts and combinations of parts disclosed, and as defined in the appended claims.

Having thus described my invention, what I 15 claim is:

1. A pulverizing apparatus comprising a casing having an inlet and an outlet, means for supplying material to be pulverized to said inlet, means for moving a current of air through the casing, means within said casing for pulverizing said material comprising rotatable members, means for directing said material into contact with the radially outer portions of said members, and means independent of said members for redirecting said material back and forth through the plane of rotation of said members to said outlet.

2. A pulverizing apparatus comprising a casing 30 having an inlet and an outlet, means for supplying material to be pulverized to said inlet, means for moving a current of air through the casing, means within said casing for pulverizing said material comprising a set of rotatable members and a set of stationary members adjacent thereto, means for directing said material into contact with the radially outer portions of said rotatable and stationary members, and means for redirecting said material into contact with radially inner portions of said rotatable and stationary members.

3. A pulverizing apparatus comprising a casing having an inlet and an outlet, means for supplying material to be pulverized to said inlet, means for moving a current of air through the casing, means within said casing for pulverizing said material comprising a set of rotatable members and a set of stationary members arranged in a plane adjacent and parallel to the plane of rotation of said rotatable members, and means independent of said members for directing said material back and forth through said planes.

4. A pulverizing apparatus comprising a casing having an inlet and an outlet, means for supplying material to be pulverized to said inlet, means for moving a current of air through the casing, means within said casing for pulverizing said material comprising a set of rotatable members and a set of stationary members arranged in a plane adjacent and parallel to the plane of rotation of said rotatable members, means for directing said material into contact with the radially outer portions of said rotatable members, and means independent of said members and said means for moving a current of air through the casing for redirecting said material back and forth through said planes to said outlet.

5. A pulverizing apparatus comprising a casing having an inlet and an outlet, means for supplying material to be pulverized to said inlet, means for moving a current of air through the casing, means within said casing for pulverizing said material comprising a set of rotatable members, means for directing said material into contact with the radially outer portions of said mem-

bers, means for redirecting a portion of said material into contact with a radially inner portion of said members, and means for returning another portion of said material into contact with said radially outer portions.

6. A pulverizing apparatus comprising a casing having an inlet and an outlet, means for supplying material to be pulverized to said inlet, means for moving a current of air through the casing, means within said casing for pulverizing said material comprising a set of rotatable members and a set of stationary members adjacent thereto, means for directing said material into contact with the radially outer portions of said rotatable and stationary members, means for redirecting a portion of said material into contact with radially inner portions of said rotatable and stationary members, and means for returning another portion of said material into contact with said radially outer portions of said rotatable and stationary members.

7. Pulverizing apparatus comprising a casing having an inlet and an outlet, means for supplying material to be pulverized to said inlet, means for moving a current of air through the casing, means within said casing for pulverizing said material comprising a set of rotatable radial bars and a set of stationary radial bars arranged in a plane adjacent and parallel to the plane of rotation of said rotatable bars, and means for directing said material back and forth through said planes.

8. Pulverizing apparatus comprising a casing having an inlet and an outlet, means for supplying material to be pulverized to said inlet, means for moving a current of air through the casing, means within said casing for pulverizing said material comprising a set of rotatable radial bars and a set of stationary radial bars arranged in a plane adjacent and parallel to the plane of rotation of said rotatable bars, and baffle means for directing said material back and forth through said planes.

9. Pulverizing apparatus comprising a casing having an inlet and an outlet, means for supplying material to be pulverized to said inlet, means for moving a current of air through the casing, means providing a plurality of pulverizing zones connected by an annular passage, means adjacent to the inlet for crushing the material and distributing it to said passage free from relatively large foreign bodies, a set of revoluble and stationary members adjacent to the outlet, and means independent of said members and said means for moving the air through the casing for directing material from said passage into contact with said members a plurality of times as the material passes against the centrifugal force imparted thereto by said revoluble members towards said outlet.

10. Pulverizing apparatus comprising a casing having an inlet and an outlet, means for supplying material to be pulverized to said inlet, means for moving a current of air through the casing, means providing a plurality of pulverizing zones connected by an annular passage, means including revoluble hammers adjacent to the inlet for crushing the material and distributing it to said passage free from relatively large foreign bodies, a set of radially extending revoluble and stationary members adjacent to the outlet, and means independent of said means for moving air through the casing for directing material from said passage into contact with said members a plurality of times as the material passes against

the centrifugal force imparted thereto by said revoluble members towards said outlet.

11. Pulverizing apparatus comprising a casing having an inlet and an outlet, means for supplying material to be pulverized to said inlet, means for moving a current of air through the casing, means providing a plurality of pulverizing zones connected by an annular passage, means including revoluble hammers adjacent to the inlet for crushing the material and distributing it to said passage free from relatively large foreign bodies, a set of radially extending revoluble and stationary members adjacent to the outlet, means independent of said means for moving air through the casing for directing material from said passage into contact with said members a plurality of times as the material passes against the centrifugal force imparted thereto by said revoluble members towards said outlet, and a re-
20 jector device arranged to return for further treatment coarse material which escapes to the outlet.

12. Pulverizing apparatus comprising a casing having an inlet and an outlet, means for moving a current of air through the casing, means providing a crushing zone and a fine grinding zone, said crushing zone comprising a first stage and a second stage, a revoluble wheel arranged in said first stage, a plurality of hammers mounted on said wheel, and means comprising a scroll-shaped liner surrounding said wheel and having an opening communicating with the second stage whereby crushed material is conducted from the first stage to the second stage while maintaining the velocity of the whirling movement set up in the first stage.

13. A pulverizing mill comprising a casing having an inlet and an outlet, means providing a crushing zone and a fine grinding zone, a plurality of hammers mounted to move about an axis in said crushing zone, a set of revoluble and stationary radially extending bars in said fine grinding zone, means for moving a current of air through the casing from the inlet to the outlet, and means beyond the fine grinding zone 45 for redirecting material back to the fine grinding zone against the centrifugal force imparted to said material by the revoluble bars.

14. A pulverizing mill comprising a casing having an inlet and an outlet, means providing a crushing zone and a fine grinding zone, a plurality of hammers mounted to move about an axis in said crushing zone, a set of revoluble and stationary radially extending bars in said fine grinding zone, means for moving a current 55 of air and solid particles through the casing from the inlet to the outlet, and means in the fine grinding zone for directing the current of air and solid particles from adjacent to the casing to the axis of rotation of the revoluble radially extending bars and into contact with said revoluble and stationary bars a plurality of times.

15. A pulverizing mill comprising a casing having an inlet and an outlet, means providing a crushing zone and a fine grinding zone, a plurality of hammers mounted to move about an axis in said crushing zone, a set of revoluble and stationary radially extending bars in said fine grinding zone, means for moving a current of air and solid particles through the casing 65 from the inlet to the outlet, means providing a plurality of passes for air and solid particles across the revoluble radially extending bars, said passes extending inwardly and concentrically of each other, and means in the crushing zone for distributing material to the first pass.

16. A pulverizing mill comprising a casing having an inlet and an outlet, means providing a crushing zone and a fine grinding zone, a plurality of hammers mounted to move about an axis in said crushing zone, a set of revoluble and stationary radially extending bars in said fine grinding zone, means for moving a current of air and solid particles through the casing from the inlet to the outlet, means providing a series of concentric and interconnected passes in said fine grinding zone, said revoluble radially extending bars tending to carry solid particles from an inner to an outer concentric pass and said current of air tending to carry solid particles from an outer to an inner pass, and means in said crushing zone for distributing material to the outer of said series of passes.

17. A pulverizing mill comprising a casing having an inlet and an outlet, means providing a crushing zone and a fine grinding zone, a plurality of hammers mounted to move about an axis in said crushing zone, a set of revoluble and stationary radially extending bars in said fine grinding zone, means for moving a current of air and solid particles through the casing from the inlet to the outlet, means providing three passes for air and solid particles across the revoluble radially extending bars, said passes extending inwardly and concentrically of each other, means cooperating with the stationary radial bars for causing a portion of the current of air and solid particles leaving the second pass to be returned to the inlet of the first pass, and means in the crushing zone for distributing material to the first pass.

18. In a pulverizing mill comprising a casing having an inlet and an outlet, a crushing zone and a fine grinding zone, suction means for causing a current of air to flow through said zones for carrying pulverized material, a series of stationary and rotating radial bars in said fine grinding zone, means beyond the rotating bars for redirecting flow into the vicinity of the stationary bars, and means cooperating with the stationary bars for splitting the redirected flow and for causing a split portion to move radially outward for mixture with flow entering the fine grinding zone.

19. A pulverizing mill comprising a casing having an inlet and an outlet, a shaft, a hub mounted on said shaft, a first and second wheel arranged on said hub, a plurality of hammers mounted on said wheels, a set of peripherally spaced radial bars fixed to said hub, a set of stationary inwardly extending radial bars located between said second wheel and said first mentioned radial bars, spacing webs integral with the stationary bars, an annular member beyond said first mentioned radial bars and arranged intermediate said webs, means for moving a current of air through the casing from the inlet to the outlet, said webs and annular member causing air to make a plurality of passes across the radial bars, and blade means associated with the second wheel for withdrawing a portion of the air leaving the second pass and for returning the same to the first pass.

20. A pulverizing mill comprising a casing having an inlet and an outlet, a shaft, a hub mounted on said shaft, a first and second wheel arranged on said hub, a plurality of hammers mounted on said wheels, a set of peripherally spaced radial bars fixed to said hub, a set of stationary inwardly extending radial bars located between said second wheel and said first

- mentioned radial bars, spacing webs integral with the stationary bars, an annular member beyond said first mentioned radial bars and arranged intermediate said webs, means for moving a current of air through the casing from the inlet to the outlet, said webs and annular member causing air to make a plurality of passes across the radial bars, and blade means associated with the second wheel for withdrawing a portion of the air leaving the second pass and for returning the same to the first pass.
21. Pulverizing apparatus comprising a casing having an inlet and an outlet, means for supplying material to be pulverized to the inlet, means for moving a current of air through the casing, a first impact wheel having a plurality of hammers, a second impact wheel having a plurality of hammers extending radially outwardly beyond the hammers on the first impact wheel, a plurality of spaced stationary bars radially disposed in a plane adjacent and parallel to the plane of the second impact wheel, a plurality of movable bars radially disposed in spaced relationship in a plane adjacent and parallel to the plane of the stationary bars, means causing the material in the zones of the stationary and movable bars to flow generally in a radially inward direction, and means for rotating the impact wheels and the movable bars.
22. Pulverizing apparatus comprising a casing having an inlet and an outlet, means for supplying material to be pulverized to the inlet, means for moving a current of air through the casing, a first impact wheel having a plurality of hammers, a second impact wheel having a plurality of hammers extending radially outwardly beyond the hammers on the first impact wheel, a plurality of spaced stationary bars radially disposed in a plane adjacent and parallel to the plane of the second impact wheel, a plurality of movable bars radially disposed in spaced relationship in a plane adjacent and parallel to the plane of the stationary bars, the stationary and movable bars extending radially outward to approximately the same extent as the hammers on the second impact wheel and being greater in number than the hammers on the impact wheels, means causing the material in the zones of the stationary and movable bars to flow generally in a radially inward direction, and means for rotating the impact wheels and the movable bars.
23. Pulverizing apparatus comprising a casing having an inlet and an outlet, means for supplying material to be pulverized to the inlet, means for moving a current of air through the casing, a first impact wheel having a plurality of hammers, a second impact wheel having a plurality of hammers extending radially outwardly beyond the hammers on the first impact wheel, a plurality of spaced stationary bars radially disposed in a plane adjacent and parallel to the plane of the second impact wheel, a plurality of movable bars radially disposed in spaced relationship in a plane adjacent and parallel to the plane of the stationary bars, means causing the material in the zones of the stationary and movable bars to flow generally in a radially inward direction, and means for superimposing on the general path of the material and air in said zones, supplementary systems of whirls which tend to keep the coarser particles in said zones while permitting the finely pulverized particles to be removed therefrom.

24. Pulverizing apparatus comprising a casing having an inlet and an outlet, means for supplying material to be pulverized to said inlet, means for moving a current of air through the casing, means within said casing for pulverizing said material comprising a plurality of rotatable pulverizing elements and a plurality of stationary pulverizing elements arranged in adjacent and parallel planes, means causing the material and air to flow in a generally radial direction in the 10 zones of said pulverizing elements, and means for superimposing on the general path of the material and air in said zones, supplementary systems of whirls which tend to keep the coarser particles in said zones while permitting the finely 15 pulverized particles to be removed therefrom.

25. Pulverizing apparatus comprising a casing having an inlet and an outlet, means for supplying material to be pulverized to said inlet, means for moving a current of air through the casing, 20 means within said casing for pulverizing said material comprising a plurality of rotatable pulverizing elements and a plurality of stationary pulverizing elements arranged in adjacent and parallel planes, means causing the material and 25 air to flow in a generally radially inward direction in the zones of said pulverizing elements, and means for superimposing on the general path of the material and air in said zones, supplementary systems of whirls which tend to keep the coarser 30 particles in said zones while permitting the finely pulverized particles to be removed therefrom.

26. The method of pulverization which comprises passing the material to be pulverized through a crushing zone and a pulverizing zone, 35 causing a current of air to flow through said zones, subjecting the material in the crushing zone to impact with moving crushing elements whereby the material is reduced in size and the material and air are caused to whirl, substantially 40 eliminating the whirling motion of the fuel and air upon leaving the crushing zone and prior to its introduction into the pulverizing zone, subjecting the material in the latter zone to a greater rate of impact with pulverizing elements than in 45 the crushing zone, and superimposing on the path of movement of the material and air through the pulverizing zone, a supplementary whirling motion to retain the coarser particles of the material in said zone while permitting the finely 50 pulverized particles to flow out of said zone.

27. The method of pulverization which comprises passing the material to be pulverized through a crushing zone and a pulverizing zone, causing a current of air to flow through said zones, 55 subjecting the material in the crushing zone to impact with moving crushing elements whereby the material is reduced in size and the material and air are caused to whirl, substantially eliminating the whirling motion of the fuel and air 60 upon leaving the crushing zone and prior to its introduction into the pulverizing zone, subjecting the material in the latter zone to a greater rate of impact with pulverizing elements than in the crushing zone, causing the material and air to 65 flow centripetally through the pulverizing zone, and superimposing on the path of movement of the material and air through the pulverizing zone, a supplementary whirling motion to retain the coarser particles of the material in said zone 70 while permitting the finely pulverized particles to flow out of said zone.
